UNITED STATES PATENT OFFICE.

THOMAS O'CONNELL, OF WATERTOWN, SOUTH DAKOTA, ASSIGNOR OF ONE-HALF TO
MORTON SPIEGEL LIEBENSTEIN, OF ESTELLINE, SOUTH DAKOTA.

COLLAR-FASTENER.

1,119,447.

Specification of Letters Patent.

Patented Dec. 1, 1914.

Application filed November 1, 1912. Serial No. 729,174.

To all whom it may concern:

Be it known that I, THOMAS O'CONNELL, a citizen of the United States, residing at Watertown, in the county of Codington and State of South Dakota, have invented certain new and useful Improvements in Collar-Fasteners, of which the following is a specification, reference being had to the accompanying drawings.

10 The present invention pertains to new and useful improvements in fasteners and relates more particularly to that class of fasteners used in conjunction with horse collars or the like.

15 The primary object of the present invention is to provide a fastener of the aforesaid character which may be easily and readily applied to the sections of the collar, which will automatically lock the sections 20 of the collar together and positively hold them against displacement and also which may be readily and easily unlocked.

The invention has for another object a simple, durable and efficient construction 25 of a device of this character, the parts of which may be cheaply manufactured, readily installed, and which will require practically no attention to maintain their proper locking connection. And the invention also 30 aims to generally improve this class of device to render them more useful and commercially desirable.

With the above and other objects in view this invention consists in the novel arrangement, combination, formation and construction of parts which will be hereinafter more 35 fully described and particularly pointed out in the appended claims.

In the accompanying drawings has been 40 illustrated the simple and preferred form of the invention it being, however, understood that no limitation is necessarily made to the precise structural details herein exhibited but the right is reserved to any 45 changes, alteration or modification that come within the scope of the invention without departing from the spirit thereof or sacrificing the efficiency of the same.

In the said drawings Figure 1 is a perspective view of the sections of the fastener in their separated position, Fig. 2 is a front elevation of the same in their locked position and showing the locking members thereof in section, and Fig. 3 is a detail sec-

tional perspective view of one of the members.

Referring to the accompanying drawings wherein like and corresponding parts are designated by similar reference characters throughout the several views the numerals 1 and 2 indicate the respective sections of the clamp each of which comprising a curved plate being bifurcated at one end thereof to form a pair of parallel shanks 3 being adapted to be secured on the opposite sides of the longitudinal indentations of the collar and provided with apertures 4 in the extremities thereof through which suitable fastening devices such as rivets may be inserted and also being provided with longitudinally extending slots 5 through which rivets or like fastening members may be inserted for securing the respective sections to the collar. From this construction it is obvious that the plates may be adjusted upon the collar by first removing the rivets inserted through the openings 4 and adjusting the plates longitudinally upon the rivets inserted through the slots 5. Suitable fastening means may then be again inserted through the openings 4 for holding the plates in their adjusted position.

The plates or members 1 and 2 are adapted to be automatically connected or coupled together, and to that end, the member 1 has 85 outstanding at a right-angle from a vertical edge thereof a vertical flange 6, about centrally from the face of which flange extends straightaway a stud or tongue 7 having a notch 8 in its upper edge, while the plate or member 2 has outstanding therefrom parallel vertical flanges 9 and 10, one flange being at the vertical edge of said member opposite the corresponding edge of the member 9, said latter flanges receiving between 90 them a slide or plate 12 adapted for engagement with said tongue or stud as presently explained.

The flanges 9 and 10 and sliding plate member 12 are provided about centrally with registering or coincident vertical slots 11 and a vertical slot 15, respectively, to receive the tongue or stud 7 with its engaging or free end suitably tapered for obvious reasons. The sliding member 12 is itself provided 105 with additional vertical slots 14 near the upper and lower ends thereof, said slots receiving suitable rivets 13 or like means for

guiding and retaining the slidable member in position, said rivets and slots providing for a limited or predetermined vertical movement of said slidable member to enable the upper end wall of the central slot 15 of the slidable member engaging or being received within the notch 8 of the tongue 7, thus enabling said slidable member and tongue to be brought into locking engagement, as in automatically coupling or connecting together the members 1 and 2 and accordingly the lower ends of the same sections.

A resilient member or spring 16 is suitably arranged within one of the slots 14, or as for that matter both slots 14 may each have disposed therein a spring, the stress or pressure of which is such as to cause the required wall of the slot 15 to normally engage the notch 8 of the tongue 7 to effect such automatic engagement therebetween as above indicated.

In order to provide for unlocking the parts, the lower end of the slidable or locking member 12 may be, or rather is, suitably extended to depend a short distance below for the convenient application of the hand thereto with that end in view.

What I claim:

30 1. A device of the type described, including detachable or separable members having outstanding at right angles thereto vertical flanges, one flange arranged at a vertical edge of one member and two of said flanges arranged parallel and spaced apart, one of said parallel flanges being at the opposed vertical edge of the other member, and a resiliently pressed slidable plate member mounted between said parallel flanges,

the first mentioned vertical flange having 40 extending from its face a notched tongue, said parallel flanges and slidable member having registering or coincident vertical slots central thereof to receive said notched tongue, said resiliently pressed slidable 45 plate having elongated slots near its ends, and guiding means projecting from said parallel flanges, received in said elongated slots.

2. A device of the type described, including detachable or separable members having outstanding at right angles thereto vertical flanges, one flange at a vertical edge of one member and two of said flanges arranged 50 parallel and spaced apart, one of said parallel flanges being at the opposed vertical edge of the other member, and a resiliently pressed slidable plate member mounted between said parallel flanges, the first mentioned vertical flange having 55 extending from its face a notched tongue, said parallel flanges and slidable member having registering or coincident vertical slots central thereof to receive said notched tongue, said resiliently pressed slidable plate having elongated slots near its ends, and guiding means projecting from said parallel flanges received in said elongated slots, said slidable locking member having one end 60 extending beyond said separable members when the device is in a coupled position for the purpose specified.

In testimony whereof I hereunto affix my signature in the presence of two witnesses.

THOMAS O'CONNELL.
